AUTOMOBILE BODY

Karl Wilfert, Gerlingen-Waldstadt, and Fredrich Geiger,
Boblingen, Germany, assignors to Daimler-Benz Ak-
tiengesellschaft, Stuttgart-Unterturkheim, Germany

Filed Feb. 5, 1970, Ser. No. 21,298

Claims priority, application Germany Aug. 5, 1969

Term of patent 14 years

Int. Cl. D12—08

U.S. Cl. D14—3

FIG. 4

FIG. 2

FIG. 3

FIG. 5

FIG. 6

FIG. 7

FIG. 8

FIG. 1 is a left side view of an automobile body embodying our novel design;

FIG. 2 is a front perspective view thereof with the headlights closed;

FIG. 3 is a rear view thereof;

FIG. 4 is a perspective view illustrating the left and rear side thereof with the doors in the closed condition;

FIG. 5 is a perspective view of the front and right side thereof with the doors in the closed condition;

FIG. 6 is a perspective view, similar to FIG. 5, with the doors in the opened condition, and the headlights in the closed position;

FIG. 7 is a perspective view illustrating the front and left side thereof; and

FIG. 8 is a front perspective view, similar to FIG. 2, with the headlights exposed.

The left and right side of the automobile body are of symmetrical construction.

The wheels and tires shown in broken lines are included for illustrative purposes only.

We claim:

The ornamental design for an automobile body, as shown and described.
